(57) CLAIM

What is claimed is a handbag with hinged frame, as shown and described.

DESCRIPTION

FIG. 1 is a front view of a handbag with a hinged frame. FIG. 2 is a rear view of the handbag with hinged frame of FIG. 1.

FIG. 3 is a left side view of the handbag with hinged frame of FIG. 1.

FIG. 4 is a right side view of the handbag with hinged frame of FIG. 1.

FIG. 5 is a top view of the handbag with hinged frame of FIG. 1.

FIG. 6 is a bottom view of the handbag with hinged frame of FIG. 1.

FIG. 7 is a perspective view of the handbag with hinged frame of FIG. 1 in a semi-open/unlatched state; and, FIG. 8 is a right side view of the handbag with hinged frame of FIG. 1 in a semi-open/unlatched state.

Embodiments of a handbag with a hinged frame are depicted.

For clarity, the black-and-white line drawing embodiments are not intended to convey color or material texture.

The broken lines showing stitching are part of the claimed design.
